DOUBLE PARK BENCH

Robert S. Wormser, Hillsdale, Mich., assignor to Game-Time, Inc., Litchfield, Mich., a corporation of Michigan

Filed Mar. 4, 1968, Ser. No. 10,832

Term of patent 14 years

Int. Cl. D6—01

U.S. Cl. D15—11

FIG. 2

FIG. 3

FIG. 4

FIG. 1 is a perspective view of a double park bench in accord with my new design,

FIG. 2 is a side elevational view, the opposite side being identical thereto,

FIG. 3 is an end elevational view of the double park bench design, the opposite end being identical thereto, and

FIG. 4 is a top plan view.

The ends of the leg members are shown broken away to indicate indeterminate length.

I claim:

The ornamental design of a double park bench, substantially as shown and described.
